(57) **CLAIM**

The ornamental design for a LED downlight lamp assembly, substantially as shown and described.

DESCRIPTION

In an illustrative example, the LED downlight lamp assembly may operate as a hanging downlight.

FIG. 1 is a bottom plan view showing the LED downlight lamp assembly showing my new design;

FIG. 2 is a bottom perspective view of a LED downlight lamp assembly thereof;

FIG. 3 is an elevated top perspective view of the LED downlight lamp assembly of FIG. 1.

FIG. 4 is a side elevation view of the LED downlight lamp assembly of FIG. 1, the opposite side being a mirror image thereof; and,

FIG. 5 is a bottom perspective view showing the lens portion of the LED downlight lamp assembly of FIG. 1, the lens portion being shown separately for completeness of illustration.

1 Claim, 5 Drawing Sheets
